(57) **CLAIM**

The ornamental design for an inverter battery charger, as shown and described.

DESCRIPTION

FIG. 1 is a front elevational view of an inverter battery charger showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a second perspective view thereof.

The broken lines shown in the drawings are included for the purpose of illustrating portions of the inverter battery charger that form no part of the claimed design.
